UNITED STATES PATENT OFFICE

163,845

REMOVABLE CAP FOR MECHANICAL PENCIL
OR SIMILAR ARTICLEGarfield L. Beckstrom, Chicago, Ill., assignor to
Autopoint Company, Chicago, Ill., a corporation
of Illinois

Application October 1, 1949, Serial No. 5,259

Term of patent 14 years

(Cl. D74—1)

To all whom it may concern:

Be it known that I, Garfield L. Beckstrom, a citizen of the United States, residing at Chicago, in the county of Cook and State of Illinois, have invented a new, original, and ornamental Design for a Removable Cap for Mechanical Pencil or Similar Article, of which the following is a specification, reference being had to the accompanying drawing, forming a part thereof.

In the drawing:

Figure 1 is a view in front or side elevation of a removable cap for a mechanical pencil or similar article embodying my new design, the mechanical pencil being shown in dotted outline for illustrative purposes only;

Fig. 2 is an enlarged view of the removable cap in front or side elevation; and

Fig. 3 is a top plan view thereof.

My design for a removable cap for a mechanical pencil is characterized by the spaced divided

portions which gradually and continuously taper upwardly from the lower end thereof for approximately two-thirds of its length and thereabove it is provided with offsets to form stepped portions which extend to the rounded upper end of the same, all as illustrated on the drawing.

I claim:

The ornamental design for a removable cap for a mechanical pencil or similar article, substantially as shown and described.

GARFIELD L. BECKSTROM.
